(No Model.)

E. HENN.

SAFETY RAILWAY CAR.

No. 295,637.

Patented Mar. 25, 1884.

UNITED STATES PATENT OFFICE.

EDUARD HENN, OF JERSEY CITY, NEW JERSEY.

SAFETY RAILWAY-CAR.

SPECIFICATION forming part of Letters Patent No. 295,637, dated March 25, 1884.

Application filed November 10, 1883. (No model.)

To all whom it may concern:

Be it known that I, EDUARD HENN, of Jersey City, in the county of Hudson and State of New Jersey, have invented certain new and useful Improvements in Safety Attachments to Railroad-Cars, of which the following is a specification.

This invention has reference to certain improvements in safety attachments to railway-cars for which Letters Patent have heretofore been granted to me under date of August 1, 1882, No. 261,923, which improvements are designed with a view to facilitate the opening of the sliding roof-sections from the inside of the car, even in case one or both of them should be obstructed for some reason or other. The improvements are also intended to produce the automatical opening of the roof-sections when the car becomes derailed and upset.

Practical experience has shown that when the sliding roof-sections of a railway-car are worked simultaneously by a common actuating mechanism from the inside of the car sometimes either one or both of these roof-sections become clogged or otherwise obstructed, in which case neither of the roof-sections could be opened, whereby the whole safety attachment becomes useless. To avoid this, the mechanism by which the roof-sections are operated has to be so arranged that they can be opened independently of each other, and that, furthermore, in case both roof-sections should be obstructed, either one or both of the roof-sections can be opened either by persons in the car, or automatically in case the car is thrown off the track and thrown over on its side.

For this purpose my invention consists of a railway-car provided with escape-openings in the roof, and with longitudinally-sliding roof-sections that are actuated by suitable mechanism from the inside of the car, which mechanism can be so adjusted that either one of the roof-sections can be moved separately or both together.

The invention further consists of the longitudinally-sliding roof-sections, which are provided with transversely-sliding auxiliary sections and with means whereby the latter are locked to the roof-sections in such a manner that the auxiliary sections may be opened from the inside of the car or automatically by the upsetting of the same.

In the accompanying drawings, Figure 1 represents a side view of a railway-car with my improved safety attachment and with part broken away. Fig. 2 is a side elevation of the mechanism for operating the sliding roof-sections, drawn on a larger scale. Fig. 3 is a bottom view of the car-roof and of the mechanism for operating the sliding roof-sections; and Fig. 4 represents a detail end view, partly in section on line $x-x$, Fig. 2, and a plan of said actuating mechanism; and Fig. 5, a vertical transverse section of the same on line $y-y$, Fig. 2.

Similar letters of reference indicate corresponding parts.

In the drawings, A represents a railway-car, the roof of which is provided with two or more escape-openings, $a-a$, of sufficient size to admit the convenient passage of persons. The escape-openings $a-a$ are closed by sliding roof-sections B, the flanged sides of which are guided in longitudinal ways $b-b$ at the outside of the roof. The longitudinally-sliding roof-sections B B abut, when in position to close the escape-openings $a-a$, against an intermediate fixed roof-section, C, which is provided with transverse end flanges, $b'-b'$, that overlap the roof-sections B B. These roof-sections are operated by suitable actuating mechanism at the interior of the car, which mechanism is supported on a hanger-plate, d, attached to the roof. The actuating mechanism consists of two sliding rack-bars, $e-e$, which latter are pivoted at their ends to upwardly-extending arms $e'-e'$, connected to the roof-sections B B. The rack-bars $e-e$ are guided parallel to each other between the hanger-plate d and a front guide-plate, d' . They are moved in opposite directions to each other by intermeshing pinions e^2-e^3 , which turn on short shafts of the hanger-plate, the pinion e^2 meshing with a gear-wheel, f, having handles $f-f'$ for operating the same. The pinion e^2 is made of such a thickness that it meshes with the front rack-bar e and with the pinion e^3 , but not with the rear rack-bar e , with which latter the pinion e^3 is in mesh, as shown clearly in Fig. 4. Thus the pinion e^2 transmits motion to the pinion e^3 and moves also one of the rack-bars. By turning, therefore, the gear-wheel f in one direction, the rack-bars are moved in opposite directions to each other, and thereby the sliding roof-sections B B moved away from the fixed roof.

section C, so as to clear the exit-openings *a a*. By turning the gear-wheel *f* in an opposite direction, the sliding roof-sections B B are moved toward the fixed roof-section C and the exit-
 5 openings *a a* closed. As the sliding roof-sections B B are liable to get clogged by ice, by the warping of the car-roof, or by other obstructions, it is necessary that the roof-sections B B can be moved independently of each other, so
 10 that in case either one should be obstructed the other will be able to move and clear the exit-openings. For this purpose levers *g g* are pivoted at opposite sides of the rack-bars to the hanger-plate *d* and front plate, *d'*, and provided with pins *g'*, which engage, respectively,
 15 longitudinal grooves of the rack-bars *ee*. Each lever *g* is provided with a handle, *g'*, for operating the same. A pin, *h*, of each lever is engaged by a check-spring, *h'*, having a projection or rest, *h''*, which spring is attached to the roof of the car. When either one of the levers *g g* is raised until its pin *h* passes above the rest *h''* of the check-spring, the lever *g* is retained in raised position, and thereby its rack-
 20 bar thrown out of gear with its pinion. In this position of the rack-bar the second rack-bar, and consequently one roof-section only, is moved when the gear-wheel *f* is turned. In case the other roof-section is to be moved, the
 25 second lever *g* and its rack-bar is raised, and thereby the connection of the latter with the motion-transmitting pinion interrupted. By lowering the lever *g*, the pin of the same passes below the rest *h''* of the check-spring *h*, so that
 30 the latter retains the lever, and thereby the rack-bar connected thereto, in lowered position, so as to mesh with its pinion.
 35 If, in case of danger, it should be found that, owing to obstructions, one of the roof-sections
 40 should be clogged and that the gear-wheel *f* cannot be turned, then one or the other of the levers *g* is raised, so that on turning the gear-wheel the unobstructed roof-section responds to the action of the gear-wheel independently
 45 of the other roof-section. Should, however, both roof-sections be obstructed, so that neither can be opened from the inside, then recourse
 50 has to be taken to an auxiliary and transversely-sliding roof-section, D, which is guided by overlapping rails *i i* or transverse arc-shaped ways *i' i'* of each roof-section B, as shown in Fig. 2. Each auxiliary section D is locked to one of the ways *i i* by a sliding and spring-
 55 pressed latch, *l*, that enters a recess of said way, and is guided at the under side of the auxiliary roof-section D. The latch *l* is made wider at the rear end and provided with flanges *l' l'*, that are engaged by the ends of a forked and weighted lever, *m*, fulcrumed to the under side of the auxiliary roof-section D. By turning the lever *m* to either side the latch *l* is withdrawn from the recess of the way *i'*, and the auxiliary roof-section D may be moved to either side on its ways without difficulty.
 60 65 In case of derailment and upsetting of the car, the weighted lever *m* will be thrown by

gravity to one side or the other of the longitudinal axis of the roof-section, and thereby the latch withdrawn, so that the auxiliary roof-section is automatically opened by the shock 70 imparted to the car when thrown on its side. The passengers in danger can thereby escape through the exit-openings and evade the danger of getting suffocated by smoke or burned with the car. The additional safeguards, thus 75 provided, adapt the car specially for railway mail, baggage, express, and passenger cars, and furnish a simple and convenient means whereby employés and passengers may escape in the event of collision of the train or derailment of 80 the car.

Having thus described my invention, I claim as new and desire to secure by Letters Patent—

1. The combination of a car-roof having transverse escape-openings, longitudinally-sliding roof-sections guided on ways of the roof, mechanism arranged in the interior of the car for moving the sliding roof-sections in opposite directions, and mechanism, substantially as described, whereby either roof-section may be moved independently of the other, substantially as set forth. 85 90

2. The combination of a car-roof having transverse escape-openings, sliding roof-sections guided in ways of the roof, parallel rack-bars connected to said roof-sections, pinions turning on a fixed hanger-plate and engaging said rack-bars, a gear-wheel meshing with one of said pinions and having handles, levers pivoted to said hanger-plate and engaging grooves 100 of said rack-bars, and check-springs which engage said levers and retain them, together with the rack-bars, in raised or lowered position, substantially as set forth. 95

3. In a safety attachment to railway-cars, the combination of a car-roof having transverse escape-openings, longitudinally-sliding roof-sections guided on ways of the roof, auxiliary transversely-sliding roof-sections guided on ways of the main sections, and means 110 whereby the auxiliary roof-sections are locked to or released from the main sections, substantially as described. 105

4. As an improvement in safety attachments to railway-cars, the combination of a car-roof having transverse escape-openings, sliding roof-sections guided on ways of the roof, auxiliary transversely-sliding roof-section guided on ways of the main sections, a spring-actuated slide-latch for locking the auxiliary section, and a fulcrumed and weighted lever engaging said latch to open it automatically by gravity when the car is tilted, substantially as set forth. 115 120

In testimony that I claim the foregoing as my invention I have signed my name in presence of two subscribing witnesses. 125

EDUARD HENN.
